UNITED STATES PATENT OFFICE.

CHARLES F. PIERCE, OF CHICAGO, ILLINOIS.

REFRIGERATOR-CAR.

SPECIFICATION forming part of Letters Patent No. 257,830, dated May 9, 1882.

Application filed August 15, 1881. (No model.)

To all whom it may concern:

Be it known that I, CHARLES F. PIERCE, a citizen of the United States, residing at Chicago, in the county of Cook, in the State of Illinois, have invented certain new and useful improvements in Refrigerator-Cars, which are fully set forth in the following specification, reference being had to the accompanying drawings, in which—

10. Figure 1 represents a transverse section of a car containing my improvement; Fig. 2, a side elevation of a part of the ice-pan; Fig. 3, a longitudinal section of a portion of the car, taken on the line *xx* in Fig. 1; and Fig. 4, a 15 transverse section of the ice-pan and drip-trough on an enlarged scale.

My invention relates to the devices for supporting the ice in refrigerating-cars and for carrying off the drip, the object being to provide 20 for free circulation of air and prevent the drip from condensation falling into the car.

The improvements relate to the special construction, arrangement, and support of the ice-pan and drip-trough within the car, all of 25 which will be hereinafter fully described, and the special improvements which are believed to be new and which I desire to secure by Letters Patent will then be pointed out definitely in the claims.

30. In the drawings, A represents a refrigerator-car of any well-known construction and general features—that is, so far as the walls, roof, and floor are concerned. I shall not enter into a detailed description of the car in these particulars, as they constitute no part of my present invention, and any style may be adopted suitable for the purpose, though I have shown in the drawings the construction of the car generally known as the "Tiffany."

40. An ice-pan, B, is provided, nearly as long as the car, and with its sides inclined or V-shaped, as shown in the drawings. These sides may be arranged at any convenient angle, preferably not less than forty-five degrees, however; 45 and the pan may be made of any suitable metal, though I prefer to use galvanized iron. The pan is made water-tight, except as hereinafter described, and is of somewhat less width than the interior of the car. A series of small 50 holes, b, is made in each side of the pan, close to the angle made by the meeting of the two

sides; or the holes may be in the angle; or a narrow slit may be left at the angle; and the pan is also provided with a series of slats, C, preferably of wood, on which the ice rests when placed in this pan. These slats may run lengthwise or crosswise of the pan. I have shown the former arrangement, which is the one I prefer.

In the upper part of the car a series of metallic straps or hangers, D, are arranged, being attached to the sides of the car and inclining downward as they extend inward, to correspond with the slope of the sides of the pan, which is supported on these hangers. The pan reaches nearly to the top of the car, but space is left sufficient for the free circulation of air, which is also provided for by the open spaces at the sides of the pan, so that free circulation of air is allowed around the pan and in contact with the ice. Strips of wood E are arranged on the hangers between them and the pan, which provides for the arrangement of a trough or gutter, F, underneath the lower portion of the pan. This gutter may be of sheet metal, and is arranged upon the hangers, being fitted underneath the wooden strips E, the latter extending not quite down to the angle of the pan, as shown in Fig. 4 of the drawings. I prefer, however, to make the gutter of wood, 80 for this will prevent condensation on the under surface, which would produce a slight drip into the car. When the gutter is made of metal it is desirable to line its under surface with wooden strips G, fitting the space between the hangers and covering the under sides of the gutter. These lining-strips may be attached to the gutter in any suitable way, or supported on the cross-bars in the inside of the car, as may be convenient. The gutter 90 has a dip or inclination toward one end of the car, in which is arranged a waste-pipe, H, into which the gutter discharges. The waste-pipe leads down to a trap, I, at the bottom of the car, where the waste water is emptied from time 95 to time.

Suitable openings are provided in the roof of the cars above the pans, through which ice is introduced to fill the pans. These openings must of course be protected by doors and plugs, as usual, to prevent the escape of air. The waste from the ice escapes through the

openings in the bottom of the pan to the gutter, and is discharged into the waste-pipe. The sloping sides of the pan also carry all the moisture formed by condensation on the under surface into the gutter, thereby preventing drip into the body of the car upon the articles which may be placed therein. Obviously, therefore, the car will be kept substantially dry. At the same time a large surface of ice 10 is provided, running the length of the car, over and around which a free circulation of air is allowed, so that the air within the car will be satisfactorily refrigerated. A cold dry car is thus provided, within which perishable substances 15 may be transported successfully from place to place.

Having thus described my invention, what I claim as new, and desire to secure by Letters Patent, is—

- 20 1. In a refrigerator-car, the car roof or ceiling, in combination with a V-shaped ice-pan arranged lengthwise of the car, and supported a short distance from the ceiling, whereby open spaces are provided between the side edges of the pan and the ceiling for the free circulation of air, substantially as described.
- 25 2. In a refrigerator-car, an ice-pan provided with inclined or sloping sides with waste-openings at the bottom, in combination with a separate waste-gutter arranged underneath the pan, substantially as described.
- 30

3. The ice-pan B, having its sides sloping downward and inward, and provided with waste-openings at the angle, in combination with a separate waste-gutter, F, arranged underneath 35 the angle of the pan, and hangers D, substantially as described.

4. The ice-pan B, having sloping sides, in combination with the hangers D, wooden strips E, and gutter F, substantially as described. 40

5. The car-body A, in combination with the sloping ice-pan B, of less width than the interior of the car, and arranged lengthwise in the upper part of the latter on suitable supports, and a separate waste-gutter, F, substantially as described. 45

6. The ice-pan provided with sloping sides, in combination with the waste-gutter F and separate waste-pipe H, substantially as described. 50

7. The sloping ice-pan B, in combination with the separate metallic gutter F and wooden sheathing strips G, arranged to cover the under sides of the gutter, substantially as and for the purpose set forth.

CHARLES F. PIERCE.
